(57) **CLAIM**

The ornamental design for an energy storage device, as shown and described.

DESCRIPTION

FIG. 1 shows a front view of an energy storage device.

FIG. 2 is a perspective view thereof.

FIG. 3 is a side view thereof.

FIG. 4 is a top view thereof.

FIG. 5 is a bottom view thereof; and,

FIG. 6 is a rear view thereof.

The broken lines in the drawings illustrate portions of the energy storage device which form no part of the claimed design.

1 Claim, 5 Drawing Sheets

FIG. 1

FIG. 2

FIG. 3

FIG. 4

FIG. 5

FIG. 6
